UNITED STATES PATENT OFFICE

JEANNE F. GREIG, OF LONDON, ENGLAND, ASSIGNOR TO THE CHARNAUX PATENT
CORSET COMPANY LIMITED, OF LONDON, ENGLAND

DESIGN FOR A BRASSIÈRE

Application filed December 17, 1932, Serial No. 46,470, and in Great Britain September 14, 1932. Term of patent 14 years.

To all whom it may concern:

Be it known that I, JEANNE F. GREIG, a subject of the King of Great Britain, residing at 66 Gloucester Place, London, England, have invented a new, original, and ornamental Design for Brassières, of which the following is a specification, reference being had to the accompanying drawing, forming part thereof.

The figure is a plan view of a brassière showing my new design.

I claim:

The ornamental design for a brassière, as shown.

JEANNE F. GREIG.
